POLE SETTING APPARATUS

Nicholai M. Erdahl, Edgerton, Wis., assignor to
 Highway Trailer Company, Edgerton, Wis., a
 Corporation of Wisconsin

Application March 13, 1929. Serial No. 346,656

16 Claims. (Cl. 255—22)

This invention relates to earth excavating machines of the portable self-propelled type, having a power driven earth auger, adapted for boring holes for telephone poles, fence posts and the like; the invention more particularly resides in the novel provision of auxiliary mechanism of simplified construction, conveniently arranged on the machine, and has for a main object to provide apparatus in the nature of a derrick for use in conjunction with the boring auger, and adapted for erecting and setting the poles, posts, etc. in the holes immediately following the completion thereof by the earth auger. Another object is to provide means for guiding the auger shaft throughout its entire range of reciprocatory movement. A further object resides in the provision of improved means for locking the auger shaft at a plurality of positions of longitudinal adjustment independently of the rotation thereof. The invention consists in certain features and elements of construction, in combination as herein shown and described, and as indicated by the claims.

In the drawings:

25 Figure 1 is a side elevation of a machine embodying the present invention; parts being broken or shown in section to show details of construction.

30 Figure 2 is a fragmentary front elevation showing the auger shaft in telescoped relation in the derrick mast.

Figure 3 is a vertical section taken substantially centrally through the mast and auger shaft.

35 Figure 4 is a fragmentary transverse section taken centrally through the winding drum of the winch, (with cable omitted) as indicated at line 4—4 on Fig. 1.

40 Figure 5 is a longitudinal section showing the power take off for the winding drum of the winch, (with cable omitted from the drum) taken substantially as indicated at line 5—5 on Fig. 4.

Figure 6 is a detail view showing partially in side elevation the casing or head by which the auger is carried, and showing in section, axial with respect to the auger shaft, certain drive connections for operating said shaft.

Figure 7 is a detail section taken as indicated at line 7—7 on Figure 6.

For the purpose of illustration, the present invention is shown applied to a tractor vehicle, 10, of the self-propelled type, equipped with the usual endless traction belts, 11, trained over front and rear sprocket wheels, 12 and 13 respectively. Mounted on the frame support, 14, centrally, at the front end of the vehicle is the

boring head, 15, which includes an auger shaft, 16, having a spiral auger, 17, rigidly secured to its lower end. Said auger shaft is preferably rectangular in cross section, and has one face formed as a toothed rack, 18, by means of which the shaft and its auger are longitudinally reciprocated for feeding into the earth, or for raising it upon completion of the hole. It will be understood that the auger and its shaft are rotated and reciprocated by suitable drive connections, (or forming part of the present invention,) and a suitable illustration of a type of mechanism for accomplishing such movements of the auger and its shaft is shown in Spowart Patent No. 1,511,433, dated Oct. 14, 1924.

In Figures 6 and 7 I show a portion of such drive connections. In the vehicle illustrated the drive for the auger shaft is derived from the engine which propels the tractor, and this drive includes a pair of shafts, 100 and 101. The shaft, 100, carries a bevel pinion, 102; the shaft, 101, is telescoped within the shaft, 100, and terminates in a bevel pinion, 103. The bevel pinion, 102, meshes with a ring gear, 104, which is secured to a transverse flange, 105, formed on the guideway in which the squared auger shaft, 16, is mounted for reciprocation. Thus the rotation of the shaft, 100, and its pinion, 102, causes rotation of the auger shaft, 16, and the auger, 17, carried at the lower end thereof. The pinion, 103, meshes with the teeth, 106, on the under side of a gear member journaled for rotation concentrically with the gear, 104. Teeth, 107, on the upper side of said gear member mesh with a bevel pinion, 108, journaled on a shaft, 109, which is mounted in the flange, 105. Thus the rotation of the flange, 105, in turning the auger shaft, does not interfere with the meshing of the pinion, 108, and the gear teeth, 107. The bevel pinion, 108, is integral with a spur pinion, 110, which in turn meshes with the spur gear, 111, integral with a second spur gear, 112, said gears being journaled also in the flange, 105. The latter is journaled in position to mesh with the rack teeth formed on one face of the square shaft, 16, so that rotation of the gear, 112, serves to move the shaft, 16, longitudinally within the guide, of which the flange, 105, is a part. The control of shafts, 100 and 101, for separate or simultaneous operation to accomplish rotation of the auger shaft, and also longitudinal adjustment thereof in its mounting, may be accomplished by any suitable clutch devices, not shown, for connecting these shafts with the tractor engine.

The operating levers, 21 and 22, control the

- rotary and reciprocatory motions of the auger, respectively, through clutches (not shown) which are adapted to be driven from a main drive gear, 23, which is meshed with a pinion, 24, mounted 5 on a stub shaft, 25, journaled in the frame bearing, 26. Secured to the outer end of the stub shaft is a sprocket, 27, operatively driven by a flexible chain belt, 28, from a sprocket, 29, carried on the drive shaft, 30, of the engine, 31. 10 By means of these control levers the auger shaft may be either rotated or reciprocated independently of the other movement, or both movements may be effected simultaneously, as during the boring operation.
- 15 Frequently in boring holes, the surface of the ground immediately adjacent the place where the hole is to be dug is uneven or sloping, and the machine itself thus cannot be properly positioned for making a vertical boring. For this purpose the entire boring head with its auger is made adjustable about a pair of horizontal axes, disposed transversely of each other, to provide "universal" adjustment of the auger. This adjustment also permits boring holes at an angle when the occasion necessitates. The adjustment is made about an axis extending longitudinally of the machine, by a worm, 34, meshed with a worm segment, 35, secured to the outside of the drive mechanism housing, 36, which is associated and revoluble with the boring head, 15, about said axis; said worm being rigidly secured on an operating shaft, 37, journaled in bearings, 38, rigidly supported on the frame member, 14. The boring head proper is 20 adjustable independently of the housing 36 about a second horizontal axis extending transversely of the machine, by means of a worm, 39, meshed with a worm segment, 40, secured to the boring head 15; the worm segment being mounted on an upright shaft, 41, journaled in bearings, 42, integral with the housing 36. The shafts 37 and 41 each have one end formed as at 43 to receive a suitable crank (not shown) for rotating the worms and securing proper angular adjustment of the 25 boring auger.
- 25 The boring head includes a cast housing, 46, in which is enclosed the usual means for guidance of the longitudinal movement of the auger shaft. Secured on top of said housing is a combination casing and supporting bracket, 47, positioned centrally with respect to the auger shaft; with the upper end of said casing forming a seat for a tubular member 48, which is clamped rigidly thereto by the bolts 49. Said tubular member is disposed concentrically of and completely encases that part of the auger shaft extending above the 30 boring head, as may be seen in Fig. 3. Secured to the upper end of the toothed auger shaft is a guide block or head, 50, slidably engageable with the inner wall of the tubular member 48 for insuring proper guidance for the auger shaft throughout its complete range of longitudinal reciprocatory movement. This feature is of considerable importance in that it reduces the wear and tear on the various parts of the boring head which might otherwise result from the "whipping" action of the upper end of the auger shaft 35 during rotation.
- 35 The strain and wear on these parts ordinarily is great and the "whipping" action may become severe due to wear of the guides in the housing, or the auger shaft itself, resulting in a loose fit, or because of a slight bend acquired in the shaft in some manner by the auger striking an unusually hard substance in the course of operation. Boring

machines of this character frequently encounter earth of an adhesive nature, as clay, mud, etc., which packs and clings to the spiral surfaces of the auger. To quickly remove this matter, the operator usually elevates the auger out of the hole and rotates it at a high speed, and the centrifugal force set up causes the matter to dislodge itself from the auger. In this position of the auger, the major portion of the auger shaft extends above the guide means in the housing 46, and of course, the unusual speed of rotation greatly increases the tendency for the upper end of the shaft to whip. These disadvantages are substantially overcome by the present provision of guidance for the upper end of the shaft.

Supported in the boring head housing 46 is a revoluble carrier for the driving mechanism, (not shown) including an upwardly extending cylindrical frame part, 55, surrounding said shaft, and bodily rotatable therewith. Threaded on the upper end of said frame part is a latch supporting block, 56, having a latch or pawl, 57, pivoted therein at 58, in position to engage the rack teeth 18 of the auger shaft. A tension spring, 59, is secured to said block and pawl, and normally tends to urge said pawl into tooth engaging position. Integral with said pawl is a trip finger, 60, which is adapted to be moved downwardly by an operating ring, 61, to move the latch out of engagement with the teeth of the rack. Said operating ring is provided with a pair of diametrically opposite pins, 62, projecting through cam slots, 63, formed in the cylindrical wall of the casing 47. One of said pins has a handle member, 64, and by rotation of this handle the operating ring is caused to move in an axial direction. Thus as the ring moves downwardly, it is caused to impinge against the trip finger, 60, which causes the pawl to be thrown out of engagement with the rack teeth and held in such position by the ring. The operating member 61, being a ring, of course insures engagement with the trip finger, regardless of the angular position of said finger. The block 56 is formed with an upwardly extending abutment, 65, positioned to engage the underside of the guide block 50 for limiting the downward movement of the auger shaft.

The tubular guide member 48 also serves as a mast or boom, forming a part of a derrick apparatus. Rigidly secured in the upper end of the tubular mast is the supporting bracket, 70, for the head sheave 71, over which is trained a flexible cable, 72. The end of said cable is provided with a hook, 73, to facilitate securing the cable to the objects, such as poles, posts, etc., for hoisting them. The other part of the cable extends downwardly and around the sheave 74, and thence is wound around the drum, 75, of the power winch. Said sheave 74 is mounted on bracket, 76, which is secured to the boring head, so as to be movable with said mast, and insure proper trainment of the cable on and off the drum at all times. The winding drum of the power winch is positioned on top and about centrally of the machine and is rigidly mounted on a vertical shaft, 77, journaled in a worm gear housing, 78, which is mounted on a supporting bracket, 79, mounted on the tubular member, 80, which houses the power drive connections from the engine to the boring head.

Keyed to the lower end of the shaft 77 is a worm gear, 81, meshed with a worm 82, mounted on a horizontally extending shaft, 83, journaled

in said worm gearing housing. A coupling, 84, connects shaft 83 with an axially aligned shaft, 85, journaled in a housing 86, and feathered on said shaft 85. Inside the housing is a gear, 87, 5 adapted to be axially shifted into or out of mesh with the main driving gear 23 by a shifting fork, 88, secured to a horizontally extending shifting rod, 89. Said rod is provided with a pair of longitudinally spaced notches, 90, adapted to be selectively engaged by a detent plug, 91, slidably seated in a recess, 92, in the housing, 86, and 10 yielding urged upward by a spring 93. Thus the detent yielding maintains said winch driving gear in or out of mesh with the main gear 23 for controlling the paying in or out of the cable.

It will be apparent that in my combination machine I have arranged the derrick apparatus in a simple, compact and convenient manner, utilizing the tubular member for the dual purpose of a mast and auger shaft guide. The mast, being rigid with the boring head, is adjustable therewith about both horizontal axes; thus, the mast may be frequently used advantageously in hoisting and setting the poles, posts, etc. especially in instances where the machine is resting on sloping or uneven ground, the mast thus being capable of adjustment to reduce the leverage and excessive straining of parts.

30 This combination machine is a great labor and time saver, and is especially useful in building and maintaining telephone or telegraph systems, road fences and the like. The machine, after being brought to the proper location, first bores 35 the hole; then the derrick is employed for hoisting the pole and setting it in the hole under some manual guidance if necessary. Thus, the operation is efficiently performed in an expeditious manner. A machine of this character may also 40 be advantageously employed in reset work, or in dismantling an old line of a telephone or telegraph system. Due to the adjustability of the boring head, the mast with the auger shaft may be rearwardly inclined, as indicated at "A" in 45 Fig. 1, so as to reduce the overall height to a minimum in travelling from place to place.

I claim:

1. An earth boring machine including a boring head angularly adjustable about a pair of transverse axes, an auger shaft carried by the head and movable therewith, said shaft being adapted 50 to have positive rotary and longitudinal reciprocatory motion imparted thereto, and locking means independent of the means for imparting 55 said motion for securing said shaft at will at a plurality of positions of longitudinal adjustment.

2. An earth boring machine including a boring head, an auger shaft carried by the head, provided with a toothed rack, and arranged to 60 have rotary and longitudinal reciprocatory motion imparted thereto, and means for locking said shaft at a plurality of positions of longitudinal adjustment, said means including a latch member engageable with the rack teeth, a fixed 65 casing member on the boring head, an operating ring disposed in the casing and having features interengaging therewith, whereby the rotation of said ring causes movement of said latch out of engagement with the rack teeth.

70 3. In the combination defined in claim 2, said ring having a plurality of outwardly projecting pins and the casing having oblique cam slots in which said pins are engaged for causing axial movement of the ring when it is rotated and thus 75 shifting the latch with respect to the rack teeth.

4. In the combination defined in claim 2, means yieldingly urging said latch member toward the rack teeth.

5. In the combination defined in claim 2, a fixed support for the latch, having an upwardly extending lug, said shaft having a cooperating stop piece, adapted to abut against said lug for limiting the downward movement of the auger shaft. 80

6. An earth boring machine, including a boring head angularly adjustable about a pair of transverse horizontal axes, a longitudinally movable auger shaft carried by the head; a derrick including a hollow tubular mast mounted on said boring head, concentrically with and encasing the upper portion of the auger shaft, a winding drum, a sheave mounted on the top of the mast, a second sheave mounted adjacent the base of the mast, and a flexible cable trained over said sheaves and directed onto the winding drum. 85

7. An earth boring machine including a boring head, an auger shaft carried by said head and adapted to have both rotary and longitudinal reciprocatory motion imparted thereto, and means independent of the means for providing said motion to the auger shaft and operable at will for 100 locking said auger shaft at a plurality of positions of longitudinal adjustment. 90

8. An earth boring machine including a boring head, an auger shaft carried by said head and adapted to have both rotary and longitudinal reciprocatory motion imparted thereto, and means independent of the means for providing said motion to the auger shaft for locking said shaft at a plurality of positions of longitudinal adjustment, said locking means being operative irrespective of the rotative position of the shaft. 105

9. An earth boring machine including an angularly adjustable boring head, an auger shaft carried by the head and adapted to have rotary and longitudinal reciprocatory motion imparted thereto, and guide means associated with the upper portion of said shaft for maintaining it in substantially true alignment throughout its entire range of longitudinal movement, said guide means including a tubular member mounted on 115 the boring head and surrounding the auger shaft, and a guide block secured to the shaft and having sliding contact with the inner wall of the tube.

10. An earth boring machine including an angularly adjustable boring head, an auger shaft carried by the head and movable therewith and adapted to have rotary and longitudinal reciprocatory movement imparted thereto; a derrick including a mast mounted on the boring head and adjustable therewith, a winch, and a flexible cable operatively associated with the mast and the winch. 125

11. An earth boring machine including a boring head angularly adjustable about a pair of transverse horizontal axes, an auger shaft carried by the head and adapted to have rotary and longitudinal reciprocatory movement imparted thereto; a derrick including a mast mounted on the boring head and movable therewith, a winch, and a flexible cable operatively associated with 130 the mast and the winch. 140

12. An earth boring machine including a boring head, a longitudinally reciprocable auger shaft carried by the head and adapted to have rotary and longitudinal reciprocatory movement imparted thereto; a derrick including a hollow mast mounted on the boring head concentrically about said shaft, a winch, and a flexible cable operatively associated with said mast and the winch. 145

13. An earth boring machine including a boring head angularly adjustable about a pair of transverse horizontal axes, a longitudinally movable auger shaft carried by the head and adapted 5 to have rotary and longitudinal reciprocatory movement imparted thereto; a derrick including a hollow tubular mast mounted on said head and disposed concentrically about said shaft, a winch, and a flexible cable operatively associated with the mast and the winch. 10
14. An earth boring machine including a boring head angularly adjustable about a pair of transverse horizontal axes, a longitudinally movable auger shaft carried by the head, a derrick including 15 a hollow tubular mast mounted on the head and disposed concentrically about said shaft, a winch, a flexible cable operatively associated with the mast and the winch, and guide means including a head secured to the upper end of the shaft 20 slidably engageable with the inner wall of said hollow mast for guiding the shaft throughout its entire range of longitudinal movement. 95
15. An earth boring machine including a boring head angularly adjustable about a pair of transverse horizontal axes, a longitudinally movable auger shaft carried by the head, a derrick including a hollow tubular mast mounted on said head and disposed concentrically about said shaft, a winch, a flexible cable operatively associated with the mast and the winch, and locking means 80 on the boring head for securing said auger shaft in a plurality of positions of longitudinal adjustment irrespective of the angular position of the hollow mast. 85
16. In a machine of the class described, a boring head angularly adjustable about longitudinal and transverse axes; an auger shaft carried by said head and adapted to have either or both rotary and longitudinal reciprocatory motion imparted thereto, and means for positively guiding the upper end of said shaft throughout its entire range of longitudinal movement. 90
